RIDING TRACTOR

Jules P. Flock, Mantua, Ohio

Application September 26, 1958, Serial No. 52,775

Term of patent 14 years

(Cl. D14—3)

FIG. 1

FIG. 2

Figure 1 is a perspective view of the riding tractor looking from left front to right rear; and

Figure 2 is a side elevational view of the riding tractor with parts removed to show the bi-level frame design.

The essential features of my design reside in those portions shown in full lines.

I claim:

The ornamental design for a riding tractor, as shown and described.
